UNITED STATES PATENT OFFICE.

ANDERS PERSON, OF CHICAGO, ILLINOIS.

NON-REFILLABLE BOTTLE.

No. 826,271.

Specification of Letters Patent.

Patented July 17, 1906.

Application filed April 17, 1905. Serial No. 255,896.

To all whom it may concern:

Be it known that I, ANDERS PERSON, a subject of the King of Sweden and Norway, residing at Chicago, Illinois, have invented certain new and useful Improvements in Non-Refillable Bottles, of which the following is a clear and correct description, reference being had to the accompanying drawings, forming a part hereof, and in which—

10 Figure 1 shows a bottle-neck with my improvement shown in central vertical section. Fig. 2 shows a bottle-neck in central vertical section with the parts within it in perspective, also showing a small part in central vertical section. Fig. 3 shows a plan view of Fig. 2 on the cutting-plane 3 3 of Fig. 2, and the broken line 2 2 indicates the cutting-plane on which the vertical sections of Figs. 1, 2, and 7 are made. Fig. 4 shows the parts 20 *b* and *l* below the plane 3 3 of Fig. 2. Fig. 5 shows the top of Fig. 4 in plan view. Fig. 6 shows the top of the parts which are inside of the walls of the bottle in plan view. Fig. 7 shows a bottle-neck constructed as a part of 25 my said new invention shown in central vertical section.

Like reference-letters denote like parts throughout.

The object of my invention is to construct 30 a non-refillable bottle which shall be economical and reliable in its action. To attain said desirable end, I construct my said new structure in substantially the following manner, namely:

35 I make the cork-chamber *o* of the bottle-neck *a* larger than the neck below said chamber and provide the neck below said chamber with a metal tube *b*, having a screw-threaded flange *j*, and beneath said flange 40 and in the material of the neck *a* is a coned chamber *n*, inside of which is an annular chamber *h*, or, in other words, there is a space between the line of the cone and the tube *b*. To the tube *b* are attached springs *l*, which 45 move in said annular chamber *h* when the tube *b* is screwed to its place. The free ends of said springs *l* click into a series of successive shoulders or stops *i*, cut into the walls of said chamber *n*. Notches *m* receive the ends

of a suitable instrument, with which to drive 50 home the screw. A gasket *k*, of suitable material, is placed between the lower face of the flange *j* and the shoulder of the neck to make a tight joint. Said tube when screwed to place is inseparable from the bottle, as the 55 springs *l* form braces which prevent the unscrewing of the tube *b*, and said parts so united remain inseparable.

Near the upper end of the tube *b* are several transverse partitions *c*, provided with 60 passages *g*, which are placed as far as possible from being in the same axial line for the purpose of thereby preventing the inserting and passing of a wire below said partitions, while at the same time liquids may flow out 65 from the bottle. Below said partitions of fixed diaphragms are a series of annular ledges *f*, to each of which are hinged valves *d*, and to their under sides are secured light springs *e*, which are fastened to the tube *b* at 70 one end, and their free ends are secured to the bottom of the valves, as shown. Said springs are to be strong enough to close the valves when the tube *b* is horizontal, so as to prevent the opening of the valves *d* and to 75 thus allow the flow of the liquid.

It is evident that in a bottle provided with my said mechanism no liquid can be passed into the bottle, while the flow of it outwardly is easy, and that it will not be possible to 80 tamper with this structure without destroying it, and thereby disclose tampering. In this case the bottle is filled before the tube *b* is screwed to its place.

What I claim is—

85 In a non-refillable bottle, a shoulder forming, with the neck, a cork-chamber, a metal tube in said neck provided with a threaded flange, a screw-threaded chamber-wall under the cork-chamber for said flange, coned 90 chamber-walls below said threaded wall, stops cut in said coned wall and springs on said tube having free ends received in said stops.

ANDERS PERSON.
